(57) **CLAIM**

The ornamental design for a pipette tip stacking tray, as shown and described.

DESCRIPTION

FIG. 1 is an isometric view of a pipette tip stacking tray showing our new design.

FIG. 2 is a top view of the pipette tip stacking tray shown in FIG. 1.

FIG. 3 is a bottom view of the pipette tip stacking tray shown in FIG. 1.

FIG. 4 is a front view of the pipette tip stacking tray shown in FIG. 1.

FIG. 5 is a cross-sectional view taken along the line 5-5 of FIG. 2.

FIG. 6 is a cross-sectional view taken along the line 6-6 of FIG. 2.

FIG. 7 is a rear view of the pipette tip stacking tray shown in FIG. 1.

FIG. 8 is a right side view of the pipette tip stacking tray shown in FIG. 1.

FIG. 9 is a left side view of the pipette tip stacking tray shown in FIG. 1; and,

FIG. 10 is a cross-sectional view taken along the line 10-10 of FIG. 2.

The features of the pipette tip stacking tray shown in phantom lines are not elements of the design of our new invention.

1 Claim, 5 Drawing Sheets
